[57] CLAIM

The ornamental design for a combined tire bumper and air gauge, as shown.

DESCRIPTION

FIG. 1 is a side elevational view of a combined tire bumper and air gauge showing my new design;

FIG. 2 is a bottom plan view thereof;

FIG. 3 is a right end elevational view thereof;

FIG. 4 is a side elevational view of another embodiment of my new design of FIG. 1;

FIG. 5 is a bottom plan view thereof;

FIG. 6 is a right end elevational view thereof;
